UNITED STATES PATENT OFFICE.

EINAR NILSEN, OF BALTIMORE, MARYLAND.

DOOR-LOCK.

1,164,849.

Specification of Letters Patent. Patented Dec. 21, 1915.

Application filed January 30, 1915. Serial No. 5,267.

To all whom it may concern:

Be it known that I, EINAR NILSEN, a subject of the King of Norway, residing at Baltimore, State of Maryland, have invented 5 certain new and useful Improvements in Door-Locks, of which the following is a specification.

The present invention relates to improvements in door locks, its object being to provide a device which is of simple construction, readily operable from the inside of the door to which it is attached, but rendering the opening of the door from the outside quite difficult unless the simple process of 15 unlocking the mechanism is understood.

To this end I provide a door lock which comprises a spindle for actuating the door bolt, said spindle being provided with a longitudinally arranged locking tumbler 20 adapted to interlock with the lock casing upon movement of a tumbler releasing member by insertion of a specially constructed key through one passage in the spindle, thus locking the door, unlocking of the door, 25 however, being accomplished only by movement of the tumbler upon insertion of said key through an independent passage of said spindle whereby to enable said releasing member to assume its initial coacting relation with respect to the tumbler.

It is also comprehended to supply independent locking means operable from the inside of the door only, which renders the locking mechanism hereinbefore mentioned 35 inoperable.

The invention comprises certain novel constructions, arrangements, and combinations of parts as will be hereinafter described and claimed.

40 In the drawings: Figure 1 is a vertical, longitudinal, sectional view through an embodiment of the invention, the door to which the same is attached being broken away and shown in section. Fig. 2 is a vertical transverse sectional view on the line 2—2 of Fig. 1. Fig. 3 is a horizontal sectional view taken on the plane indicated by the line 3—3 of Fig. 1. Fig. 4 is a vertical sectional view on the line 4—4 of Fig. 1. Fig. 5 is a 45 detail vertical section on the line 5—5 of Fig. 1. Fig. 6 is a detail sectional view through the locking mechanism of the device and taken on the plane indicated by the line 6—6 of Fig. 2. Fig. 7 is a vertical

sectional view on the line 7—7 of Fig. 2. 55 Fig. 8 is an enlarged vertical sectional view on the line 8—8 of Fig. 2, looking in the direction of the arrows. Fig. 9 is a sectional view on the line 9—9 of Fig. 3. Fig. 10 is a detail perspective view of the tubular 60 guide casing for the locking bolt. Fig. 11 is a detail elevation of the inside locking pin member. Fig. 12 is a longitudinal sectional view of the preferred embodiment of 65 a key for operating the locking mechanism of this invention. Fig. 13 is a detail sectional view showing application of a removal cap to replace outer door handle when desired.

Throughout the following detail description, and on the several figures of the drawings, similar parts are referred to by like reference characters.

Referring to the drawings, it will be noted from Fig. 1 that the embodiment of my invention consists of a lock casing 1 which is adapted to be secured in a door 2 at its swinging end and in said casing is slidably disposed a locking bolt 3 having its inner extremity operable in a tubular guide casing 75 4 which is detachably connected to the end wall of the lock casing 1. Within the casing 4 is disposed a spring 5 which normally holds the locking bolt 3 projected from the lock casing 1 and into coöperation with the 80 keeper plate 6 attached to the door jamb 7. Within the casing 4 is disposed a spring 5 which normally holds the locking bolt 3 projected from the lock casing 1 and into coöperation with the 85 keeper plate 6 attached to the door jamb 7.

Passing transversely through the lock casing 1, is a spindle 8 shown most clearly in Figs. 2 and 3 and mounted upon said spindle within the lock casing is a toothed 90 operating member 9 coöperating with the upper toothed edge of the locking bolt 3. The bolt may be retracted against the tension of the spring 5 obviously by rotation of the spindle 8, and said rotation is limited by means of the opposing shoulders 10, 10' formed on the periphery of the member 9 and which shoulders coact with a double-armed projection 11 formed on the casing 1. Sliding movement of the bolt is furthermore guided by the lug 12 formed on the casing adjacent the outer end thereof and coacting with the upper edge of said bolt as shown in Fig. 1 of the drawing. Arranged in a longitudinally extending slot 13 formed in the outer portion of the spindle 8 is a pivoted locking tumbler 14, the pivot of which is indicated at 15 and the inner end of said

10 0

105

tumbler is formed with an enlarged locking head 16 which is adapted to be projected from the spindle into locking engagement with the casing 1, the projection 11 of which 5 is formed with a recess 17 to receive said head, by means to be more clearly described hereinafter.

It will be observed by reference to Fig. 2 that the outer end of the tumbler extends 10 into an enlarged hollow casing 8' formed on the spindle and as most clearly shown in Fig. 6 and Fig. 9, the tumbler head 16 is normally held in inoperative disengaged position such as most clearly depicted in Fig. 15 2 by means of a tumbler releasing member or detent 18 and slidably mounted transversely of the spindle head 8' and engaging beneath the outer end of said tumbler 14. The detent mentioned is slidable, at one 20 end, in a plug 19 having threaded connection at one side with the spindle head 8' and formed at its other side with a threaded boss 19' to receive a handle 20. The plug 19 is recessed to accommodate the detent 18 25 and in said recess is disposed a spring 21 normally holding said detent in a position with the locking tumbler engaged on its upper edge, said detent, however, being formed with a recess 18' to receive the tumbler extremity when the detent has been moved longitudinally into a position shown in dotted lines in Fig. 6 of the drawings, by any 30 implement, such as will be hereinafter specifically mentioned. The longitudinal movement of the detent just mentioned and downward movement of the outer end of the locking tumbler into recess 18' of said detent under actuation of a spring actuated pin 22 seated in a screw plug 23 and normally bearing against the upper surface of 40 said tumbler extremity, causes the inner head of the tumbler to be projected from the spindle and through the slot 9' of the bolt actuating member 9 into the recess 17 45 of the projection 11 of the casing thereby locking the bolt 2 against movement when the spindle is attempted to be rotated. As a matter of convenience of insertion of the detent into the extremity of the spindle, said 50 spindle is provided therebeneath with a threaded plug 24 which has formed therein a key-hole or passage 25 normally covered by a pivoted cap 26. It will be observed by reference to Figs. 6 and 9 that the spindle head 8' is furthermore provided with a second key-hole or passage 27 at one side in alinement with one end of the detent 18. 55

As thus far described, the operation of this device is as follows: Assuming that the 60 occupant of a house desired to lock the door from the outside he employs a key of special construction for operating the tumbler 14; this key is best shown in Fig. 12 of the drawing and consists of an outer tubular casing 28 having slidably mounted

therein a tapering tube 29 through which extends a rod 30 passing also into the casing 28. The casing 29 is held in outward projected position by the spring 31 and pressure against tube 29 causes the rod 30 to be projected therefrom in an obvious manner to those skilled in the art to which this invention refers. The key member is preferably of this form and provided with a ring 32 at one end for attachment to a chain but it will be understood that any other desired form of implement may be used in the operation of my lock. 70 75

To lock the door the key rod 30 is inserted into the key-hole 27 into contact with the detent 18 which by pressure thereagainst is moved against the tension of its spring until the tumbler 14 falls into the recess 18' of said detent under actuation of its spring. The head has thus been engaged with the projection 11 of the casing 1 and the spindle is locked against rotation by pressure on the handle 20. The key-hole passage 27 is provided with a pivoted cap 33 and the unlocking of the door has now been rendered quite difficult unless the operator is acquainted with the manner in which the tumbler may be disengaged from its locking position. This is accomplished by inserting the key rod 30 into the key-hole 25 of the plug 24 secured beneath the outer spindle end, until the rod contacts with the outer extremity of the tumbler 14 whereupon pressure thereagainst raises said tumbler against its spring member until it is freed from the recess 18' of the detent 18 allowing said detent to be actuated longitudinally by its spring 21 so as to engage beneath the tumbler end as shown in Figs. 6 and 9. This frees the spindle so that the same may be rotated by raising upwardly on the handle 20 and the locking bolt 3 thereby retracted. I preferably arrange the spindle for rotation only on upward movement of the handle 20 to make the operation of the device somewhat unusual. The spindle 8 is held in proper position in the door by the outer door plate 34 and on the opposite or inner side of the door by a similar plate 35. As a means for rendering the outer mechanism of the door lock inoperative from the inside of the door, I preferably provide the door plate 35 with a vertical groove in which is slidably mounted a locking pin 36 having a spring 36' secured thereto for providing frictional sliding action to said pin. This pin is adapted to engage in a recess 37 formed in the spindle 8 directly beneath the pin as most clearly shown in Fig. 8 of the drawings and when introduced into the recess the spindle is locked against rotation in an obvious manner. The inner end of the spindle carries the inner handle 38, integral with or having threaded connection with the enlarged head 39 adapted to be slid on to the spindle extremity and 90 95 100 105 110 115 120 125

locked in position thereon by a set screw 40 which engages in a longitudinal groove 41 formed in the upper spindle surface.

As a part of the detail construction of this lock, I preferably form the guide casing 4, which has threaded connection with the lock casing 1 as hereinbefore described, with a plurality of apertures 4' by means of which to facilitate the removal of the casing when desired as by inserting a pin or other instrument into said apertures to unscrew the tube. The handles 20 and 38 also are preferably hollow so as to enable the introduction thereto of a disinfectant such as indicated at 42 in Fig. 9 of the drawing, the handles being formed with a plurality of apertures 43 whereby the disinfectant may perform its proper function. The handles are provided with a removable cap at their ends designated 44 to enable the disinfectant to be inserted thereinto. A cap 45 is also provided to protect the boss 19' when the outer handle is removed temporarily.

It will be obvious that any desired means may be provided in my construction of lock for operating the lock tumbler from the inside of the door, though this detail of construction is not an essential feature.

Having thus described my invention, what I claim as new is:

1. The combination of a door lock comprising a casing, a spindle passing therethrough, a tumbler arranged in the spindle and adapted to interlock with the casing, releasable means engaging the tumbler and normally holding it out of interlocking engagement, and a key member for moving said releasable means longitudinally to release the tumbler for assuming locking position, said key member constituting actuating means for the tumbler for moving the same into unlocked position and permitting restoration of the releasable means to initial tumbler engaging position.

2. The combination of a door lock comprising a casing, a spindle disposed therein and having key openings arranged at different points, a tumbler pivoted intermediate its ends and arranged longitudinally in the spindle and adapted to interlock at one end thereof with the casing, means coacting with the other end of the tumbler for holding it out of locking engagement, and a key adapted for insertion in the spindle in one direction in one of the key openings for actuating said means to release the tumbler for locking engagement, said key being insertible into the spindle into another opening in another direction to actuate the tumbler for restoring said tumbler coacting means to normal position.

3. A door lock comprising a casing, a locking bolt slidably mounted therein, a spindle passing through said casing, an actuating member carried by said spindle for sliding

the bolt upon rotation of the spindle, a pivoted tumbler arranged in the spindle and normally operable therewith, a detent mounted in the spindle transversely of the tumbler and adjacent to one end thereof whereby to normally hold the tumbler in inoperative position, a key adapted to engage the detent to slide the same into a position releasing the tumbler for movement of its free end into locking engagement with the casing preventing rotation of the spindle, said key being adapted for engagement with the tumbler to disengage the same and permit the tumbler to assume its initial position.

4. A door lock comprising a casing, a locking bolt slidably mounted therein, a spindle passing through said casing, an actuating member carried by said spindle for sliding the bolt upon rotation of the spindle, a pivoted tumbler arranged in the spindle and normally operable therewith, a spring actuated detent arranged transversely of the tumbler and engaging beneath one end of the same to hold said tumbler normally in inoperative position, said detent having a recess to receive the tumbler end when moved longitudinally whereby to permit projection of the other end of the tumbler into operative locking engagement, and a key for sliding the detent.

5. A door lock comprising a casing, a locking bolt slidably mounted therein, a spindle passing through said casing, an actuating member carried by said spindle for sliding the bolt upon rotation of the spindle, a pivoted tumbler arranged in the spindle and normally operable therewith, a spring actuated detent arranged transversely of the tumbler and engaging beneath one end of the same to hold said tumbler normally in inoperative position, said detent having a recess to receive the tumbler end when moved longitudinally whereby to permit projection of the other end of the tumbler into operative locking engagement, and a key for sliding the detent against tension of its spring, said key being engageable with the tumbler to release the detent whereby to restore the tumbler to initial inoperative position.

6. The combination of a door lock comprising a casing, a spindle passing therethrough and terminating at one end in a hollow head, a tumbler pivotally mounted in said spindle and adapted to engage the casing at one end to prevent rotation of said spindle, the opposite end of the tumbler extending into the hollow spindle head aforesaid, a handle detachably secured to the spindle head, means slidably mounted in the head and adapted to engage beneath the tumbler extremity for holding the same in inoperative position, the head aforesaid having an aperture adjacent the last-mentioned

means, and a key adapted to be inserted in said aperture for moving the tumbler engaging means into position freeing the tumbler extremity whereby to permit of locking engagement of said tumbler with the casing.

7. The combination of a door lock comprising a casing, a spindle passing therethrough and terminating at one end in a hollow head, a tumbler pivotally mounted 10 in said spindle and adapted to engage the casing at one end to prevent rotation of said spindle, the opposite end of the tumbler extending into the hollow spindle head aforesaid, a handle detachably secured to the 15 spindle head, means slidably mounted in the head and adapted to engage beneath the tumbler extremity for holding the same in inoperative position, the head aforesaid having an aperture adjacent the last-mentioned 20 means, and a key adapted to be inserted in said aperture for moving the tumbler engaging means into position freeing the tumbler extremity whereby to permit of locking engagement of said tumbler with 25 the casing, the spindle head also having a second opening therein in alignment with the tumbler extremity whereby to permit of insertion of the key into coöperation with the tumbler to disengage the same from the 30 casing and render the tumbler engaging

means free to engage the tumbler for holding the same inoperative.

8. A door lock comprising a casing, a locking bolt slidably mounted therein, a spindle passing through said casing, an actuating member carried by said spindle for sliding the bolt upon rotation of the spindle, a spring actuated tumbler pivotally mounted in the spindle and normally operable therewith, a spring actuated detent slidably mounted in the spindle transversely of the tumbler and normally holding the same in inoperative position, the spindle having a key-hole to permit access to the detent for actuation of the same into a position freeing the tumbler for locking engagement with the lock casing, the spindle having a second key-hole to permit access to the tumbler for actuating the same to disengage it from the casing, a key for actuating said detent and 45 tumbler upon insertion in the respective key-holes aforesaid, and a handle carried by each end of the spindle for rotating the same.

In testimony whereof I affix my signature in presence of two witnesses.

EINAR NILSEN.
